BASEBALL GLOVE

Richard E. Bates, Ashland, Ky., and Theodore E. Javor, Roselle, Ill., assignors to Wilson Athletic Goods Mfg. Co., Inc., River Grove, Ill., a corporation of Delaware

Filed June 3, 1966, Ser. No. 2,546

Term of patent 14 years

(Cl. D2—361)

FIG. 1 is a front perspective view of a baseball glove showing our new design; and

FIG. 2 is a rear perspective view thereof.

The essential features of our design reside in the full line disclosure on the drawing.

We claim:

The ornamental design for a baseball glove, substantially as shown and described.
